CLAIM

We claim the ornamental design for a telephone, as shown and described.

DESCRIPTION

FIG. 1 is the front perspective view of a telephone showing our new design;

FIG. 2 is the front view thereof;

FIG. 3 is the rear view thereof;

FIG. 4 is the left-side view thereof;

FIG. 5 is the right-side view thereof;

FIG. 6 is the top plan view thereof; and,

FIG. 7 is the bottom plan view thereof.

The broken line consisting of unevenly sized dashes defines the boundary of the claim, which extends to the boundary but does not include the boundary; while all other broken lines in the drawing depict portions of the telephone that form no part of the claim.
